(57) **CLAIM**

The ornamental design for an electric drill, as shown and described.

DESCRIPTION

FIG. 1 is a first perspective view of an electric drill; FIG. 2 is a second perspective view of the electric drill of FIG. 1, viewed from another aspect; FIG. 3 is a front view thereof; FIG. 4 is a rear view thereof; FIG. 5 is a left side view thereof; FIG. 6 is a right side view thereof; FIG. 7 is a top view thereof; and, FIG. 8 is a bottom view thereof.

The broken lines depict portions of the electric drill in which the design is embodied that form no part of the claimed design.

1 Claim, 8 Drawing Sheets(56)
